ZERO-SETTING DEVICE

William J. Pearson, Los Angeles, Calif., assignor
to Postal Automatic Machines, Inc., a corpora-
tion of Delaware

Application October 23, 1931, Serial No. 570,621

4 Claims. (Cl. 235—144)

This invention relates to control registers adapted to be used in conjunction with any machine or mechanism wherein it is desired to control the operations thereof by means of a device which may be set for a predetermined number, and which will function to actuate any desired operation upon the exhaustion of the pre-set number, but is more especially designed to be used in conjunction with a parcel post machine such as is disclosed in my co-pending application Serial Number 367,106, filed May 29, 1929, by William J. Pearson, entitled Parcel post weighing and stamp printing machine, and may be actuated by mechanism as disclosed in my co-pending application titled Meter actuating mechanism, Serial No. 570,620, filed October 23, 1931.

The parcel post weighing and stamp printing machine just recited is designed for printing purposes, more particularly the printing of metered parcel post stamps, wherein it may be required to print a stamp bearing the name of the place of original mailing, the date, the zone number to which the package is addressed, the weight of the package, the monetary value of the stamp derived from the weight and the zone, a serial number, and such other words, phrases, figures, decorations and designations as it may be desired to print.

This invention is particularly designed to be used with mechanism in which the monetary value of the stamp is set up on type within the machine by the operation of selected keys on a keyboard and is also designed to be used in conjunction with a registering device which continuously registers within a set of numeral wheels the monetary values of the stamps printed; and also with a control register, which may be set for a predetermined monetary value, and which upon the exhaustion of the set amount will function to lock the entire machine against use until again so set, and may be so disposed as to actuate any other mechanism that may be desired.

An object of my invention is to provide a control register which upon exhaustion of the pre-set amount will actuate locking mechanism or the like, which mechanism will remain in such locked relation as to cause the entire machine to remain locked until the control register is reset for another amount of postage by authorized agents.

An object of my invention is to provide a register which may be unlocked, the pinions released from engagement with the numeral wheels, and each of the numeral wheels rotated independently of the others for the purpose of setting into

the register any desired number, representing the amount of postage purchased; should there be remaining in the register any amount of postage from a previous setting, this may remain at the will of the agency setting the register, and upon the completion of the setting of the register, the register, including the resetting mechanism, may be again locked against access.

To the above purposes my invention consists in the novel construction, arrangement and combination of parts as hereinafter described, pointed out in my claims and illustrated by the accompanying drawings in which,

Fig. 1 is a front elevation of the control register and the register actuating mechanism.

Fig. 2 is a rear elevation of the same control register, with certain parts broken away to expose other hidden parts.

Fig. 3 is a plan view of the control register.

Fig. 4 is an enlarged view of two of the numeral wheels which contain the double ratchet drive and carry-over, with one wheel sectioned to expose the interior arrangement.

Fig. 5 is an enlarged view of one of the numeral wheels showing the internal ratchet.

Fig. 6 is an end elevation of the control register frame from the right showing parts of the reset mechanism.

Fig. 7 is a sectional view of the control register taken from the right at approximately lines 7—7 in Fig. 3 showing the arrangement and disposition of the gearing of the register.

The invention is illustrated as applied to a machine having a base plate 10 and frames 12, 13, for supporting elements of the machine, the whole being enclosed in a casing 11, a portion of which is shown in Fig. 1. The frame 13 supports the control register.

The control register disclosed comprises six numeral wheels 14, 15, 16, 17, 18 and 19, of which wheel 16 is sectioned to show construction, all rotatably mounted on shaft 20, supported in frame 13. Each of the numeral wheels is provided with a carry-over gear 21; in the case of wheels 17, 18 and 19 the gears are secured directly to the numeral wheels, but in numeral wheels 14, 15 and 16 the gears 21 are drive connected by means of an internal ratchet comprising a sleeve shaft 22, carrying a ratchet bearing plate 23, on which are mounted pawls 24 engaging in internal ratchet teeth 25 on the inside face 26 of each of the numeral wheels 14, 15 and 16. Engaging each of the carry-over gears 21 are carry-over pinions 27 rotatably mounted on shaft 28 mounted in carriage 29, said carriage 29 be-

ing rockably mounted by shaft 30, to which it is secured, for the purpose of enabling the pinions 27 to be disengaged from the carry-over gears 21 for the resetting of the register. The carriage 5 29 is retained in gear engaging position with pinions 27 meshing with gears 21 by means of cam 32 mounted on shaft 31. When the cam 32 (Figs. 2 and 7) is moved away from frame 29 by turning shaft 31, the free end of frame 29 10 swings downwardly under the influence of spring 129 and carries the pinions 27 away from gears 21 to non-engaging position, the pinions 27 falling on shaft 31 which engages between the teeth of the pinions and holds them in position both to 15 be re-engaged and against rotation while disengaged. Numeral wheel 14 has a carry-over gear wheel 21 which is used in the resetting mechanism.

Each of the carry-over gears 21 is engaged with 20 an intermediate resetting gear 33, of which there are six, all rotatably mounted on a shaft 34, and adapted to be selectively engaged by a sliding gear 36 secured to a slideable and rotatable shaft 37, the end of which projects into proximity to 25 and in alignment with an opening in the casing 11 and is fitted to receive a knurled turning handle 38, so that the operator may, by manipulation of handle 38, place the gear 36 into engagement with any one of the gears 33 for resetting 30 the carry-over gear 21. The lock bolt 40 (Figs. 1 and 6) is telescopically positioned in a lock casing 94 fixed to a bracket 95 on the support 13 (Fig. 2). The lower end of bolt 40 bears upon eccentric 96. When the lock 39 is in its normal 35 position (as shown in Fig. 6) the position of the eccentric 96 forces bolt 40 upwardly through the casing 40 to seat its upper end in a recess 97 in shaft 37 to hold shaft 37 against axial or rotative movement. When the lock 39 is turned by its key 40 to unlock the shaft 37, the turning movement turns the eccentric 96 and removes its high portion from beneath the bolt 40. The spring 98 within the lock casing 94, which tends to press the bolt 40 against the eccentric, thereupon moves 45 the bolt in that direction and consequently withdraws it from recess 97 thereby freeing the shaft and permitting it to be moved by the handle 38, axially to adjust the gear 36 to a selective operative position in engagement with one of the gears 50 21 and rotatively to rotate gear 36 for resetting the selected gear 21. To prevent operation of the resetting device except by an authorized agent there is provided a locking element 39 which is permanently secured to the base 10 by a 55 portion of casing 11; the other portions of the casing 11 are locked against unauthorized access by means not shown. When turned to the left in Fig. 6, the key operated locking element 39 through link 139, pin 100 and link 131 turns 60 shaft 31 bringing its cam 32 into engagement with the rockable frame 29 and swinging the frame upwardly, to bring the carry-over pinions 27 into mesh with the carry-over gears 21 (Fig. 7); the lock 39 thus positively locks the 65 pinions 27 into mesh with the numeral wheels; lock 39 also operates lock bolt 40 to engage in a stop recess (not shown) in the shaft 37 thus preventing operation of the resetting device; upon key lock operation to release the register 70 for resetting, the locking elements operate to reset and release the locking mechanism operated by boss 66 of the register to prevent further operation of the machine when the preset amount has been exhausted in the register.

75 In addition to the recited carry-over gears 21,

the numeral wheels 14, 15 and 16 are provided with drive gears 41 which are each connected to sets of pawls 42 operating against the internal teeth 25 within each numeral wheel. The drive gears are actuated by the contacting sector gears 5 43, 44 and 45 mounted on sleeve shafts 46, 47 and 48 which are driven by gears 49, 50 and 51, which are elements of the register actuating mechanism, which constitutes no part of my present invention and which actuating mechanism forms 10 the subject of a companion application, Serial No. 570,620, filed October 23, 1931.

This meter is provided with means to allow the carry-over from one register wheel to the next 15 succeeding wheel without interference from the drive elements comprising the ratchet elements, and in addition the actuation of the register by the register actuating mechanism is so arranged that each register wheel is actuated individually and consecutively, thus allowing an interval of 20 time between each drive action to each wheel for the necessary carry-over operation of the rotation of the next succeeding numeral wheel, without interference from the operation of the drive gear before or while the carry-over operation is 25 occurring.

The racks 52, 53, and 54, a part of the register actuating mechanism, are actuated by the raising of the elevators 55, 56, and 57, which have been previously actuated to a set-up relation through 30 the various connections from the keyboard (not shown), including the gearing 58.

For the introduction into the registers of the mechanical equivalent number set-up, there is provided a set of cams, and as disclosed in this 35 form there are three cams 59, 60 and 61 set to contact their respective elevators in sequence, thus providing the recited successive drive movement. These cams are mounted on a cam shaft 62 which is driven by extensions of the drive element. To insure the positive return of all of the 40 actuating members to their original positions after a register actuating operation, there is provided on the drive element 63 a cam device 64 which through its connections operates levers 65 45 to mechanically return the racks 52, 53 and 54 to their original position.

To enable the control register to control the operations of the machine upon exhaustion of the amount for which it has been set, there is provided 50 a locking mechanism comprising a boss 66 located on the edge of the last or highest count numeral wheel, so related to the rotation of figures upon the numeral wheels that upon exhaustion of the register and the final turn over from zero to the 55 nines, which, being operated in reverse direction, would be equal to the turn of the wheels from all nines to all zeros upon inserting into the register sufficient numbers to exceed its capacity, the boss 66 is rotated to a position where it will contact 60 and actuate a pivotally mounted trip element 67 provided for that purpose; trip 67 has at its other edge on the same end relative to its pivot point a foot 68; when the trip 67 is operated by boss 66 foot 68 moves out from under the drive bar 69; 65 the drive bar being spring tensioned drops when thus released so that a pin 70 thereon is positioned to be engaged and moved longitudinally by a cam lever 71 secured on the shaft 72 upon rotation of the shaft by the cam 64 through its engagement 70 with the cam roller 90 rotatably mounted upon an arm 91 fixed to shaft 72 and projecting therefrom to position roller 90 to one side of the shaft, as shown in Fig. 1. By this arrangement arm 91 acts as a lever arm through which rotation of 75

shaft 63 and cam 64 causes a vertical movement of the roller 90 bearing upon cam 64 and a consequent oscillation of arm 91 and shaft 72. This structure is shown and described in my copending application Serial No. 570,620, filed October 23, 1931.

The cam 64 engaging to actuate shaft 72 only at the completion of a printing operation consequently operates to engage pin 70 and thereby move the drive bar 69 in a longitudinal direction which operation actuates locking elements, not shown, which lock the machine against operation until the control register is again set for additional operation.

15 Thus there is provided a locking means whereby the machine may be locked against further operations upon or after the exhaustion of the number set into the control register.

Upon the operation of resetting the control register, the locking members are released and returned to normal position, by means of elements extended from the lock 39 and its connections, these elements including a crank-shaft 73 to which is connected drive bar 74 attached to lever 75. This lever is secured to and operates shaft 76, to one end of which is secured a setting lever 77 designed to contact the drive bar 69 and raise it out of the path of the cam lever 71. Upon subsequent setting of the register numeral wheels 30 and the consequent turning of the last numeral wheel 19 upon which the boss 66 is situated, the removal of the boss 66 will allow the trip 67 to again take its normal position in the path of the boss 66, which position sets the foot 68 under the drive bar 69, thus maintaining it in a position removed from the path of the cam lever 71.

To prevent frictional drag or back play or reverse movement of the numeral wheels either while being operated or when being reset, and to provide means for centering automatically the numerals on the register wheels while being reset, there is provided a set of spring retainers or pawls 79 mounted on a shaft 78 and operating against the gear wheels 33.

45 While the form of mechanism here shown and described, is admirably adapted to fulfill the objects primarily stated, it is to be understood that it is not intended to confine the invention to the one form of embodiment herein disclosed, for it 50 is susceptible of embodiment in various forms, all coming within the scope of the claims which follow.

I claim:

1. In a control register, a series of numeral wheels, carry-over pinions for said numeral wheels, means supporting said carry-over pinions and normally positioning said pinions in engage-

ment with said numeral wheels, reset means including a slidably mounted rotatable shaft, a toothed element on said shaft adapted to be selectively positioned by axial adjustment of said shaft to engage one of said numeral wheels, means normally holding said shaft against axial or rotative movement with said toothed element in disengaged position, and means for removing said pinions from engagement with said numeral wheels and for releasing said shaft to permit said toothed element to be engaged with said numeral wheels for resetting said numeral wheels.

2. In a control register, a series of numeral wheels, carry-over pinions for said numeral wheels, a rockably mounted support for said carry-over pinions normally positioning said pinions in engagement with said numeral wheels, reset means including a rotatable shaft, means normally holding said shaft against movement, a rotatable control shaft operatively connected with said holding means and said support and manually operable means for operating said control shaft for simultaneously rocking said support to remove said pinions from said numeral wheels and releasing said shaft to permit resetting of said numeral wheels.

3. In a control register, a series of numeral wheels, carry-over pinions for said numeral wheels, means supporting said carry-over pinions and normally positioning said pinions in engagement with said numeral wheels, reset means including a rotatable shaft, means normally locking said shaft against movement, a manually operable key lock, and means controlled by said key lock for removing said pinions from engagement with said numeral wheels and for releasing said shaft to permit resetting of said numeral wheels.

4. In a control register, a series of numeral wheels, carry-over pinions for said numeral wheels, means supporting said carry-over pinions and normally positioning said pinions in engagement with said numeral wheels, reset means including a slidably mounted rotatable shaft, a toothed element on said shaft adapted to be selectively positioned by axial adjustment of said shaft to engage one of said numeral wheels, a shaft lock normally engaging said shaft and holding said shaft against axial or rotative movement with said toothed element in disengaged position, and a manually operable key lock operatively connected with and controlling said pinion-supporting means and said shaft lock for removing said pinions from engagement with said numeral wheels and releasing said shaft lock from said shaft.

WILLIAM J. PEARSON.
